VEHICLE DIRECTION SIGNAL

Frank Vasarhely, Cleveland, Ohio

Application April 19, 1939, Serial No. 268,713

2 Claims. (Cl. 177—327)

My invention relates to a vehicle signaling device and in particular to that type of device which serves to warn all traffic at the rear when the vehicle, upon which it is installed, turns to 5 the right, left or stops.

The main object of the device is to provide a simple structure that consists of directional symbols and a means for operating said symbols.

Another object is to provide a switch device 10 which may be mounted on the dash, steering wheel or post, and which operates the shutters inside of the illuminated directional symbol housing to signal the desired turn or stop.

These and other objects and advantages may 15 be readily seen and noted from the following specification and its accompanying illustrations, in which:

Fig. 1 is a front view of the directional symbol housing indicating a left turn.

Fig. 2 is a top plan view of the inside of the 20 housing with the cover removed.

Fig. 3 is a view similar to Fig. 1 but indicating a right turn.

Fig. 4 is an end view of the device with the 25 lamp box in section.

Fig. 5 is a section on lines 5—5 of Fig. 2.

Fig. 6 is a front elevation partly in section of 30 one of the shutters, contact and magnet, in the closed position.

Fig. 7 is a longitudinal section of the directional 35 switch.

Fig. 8 is a section on line 8—8 of Fig. 7.

Fig. 9 is a section on line 9—9 of Fig. 7.

Fig. 10 is a fragmentary front elevation of an 35 instrument board showing the directional switch mounted thereon.

Fig. 11, a diagrammatic wiring system.

Again referring to the illustrations, a directional symbol housing is indicated at 10 and is 40 substantially of a rectangular shape with the rear corners beveled as shown in Fig. 2.

A darkened glass 12 has transparent insignia 12a thereon substantially in the middle thereof, as illustrated in Figs. 1 and 3, and is mounted 45 within a frame portion 13 in the front face of the housing 10.

A reflector 14 of a concave shape is secured 50 within the housing 10 rearward of the glass 12, and is secured to the housing, by welding or the like, at approximately three points, the center point 14a of the concave surface being secured to the rear inner wall of the housing 10, while the bent outer ends 14b of the reflector are secured to the inner surface of the front wall of the housing 55 adjacent the ends of the glass 12.

The bent ends 14b form a retaining wall for the glass 12 which fits within insulated channels 15 in the groove formed by the extended front portion 13 of the housing 10 and the bent ends 14b of the reflector 14.

Ears 16 and 17 project forwardly from the top and bottom edge of the reflector 14 adjacent the bent ends 14b, and a pair of pivot spindles 18 and 19 are mounted therebetween in a vertical position as shown in Fig. 6, the ears being pressed 10 down upon the spindle points.

Shutters 20 and 21 of a non-magnetic material are pivotally mounted on the spindles 18 and 19, respectively, the split curved ends 22 encircling the spindles at the top and bottom. V shaped 15 portions 20a and 21a are cut in the outer edge of said shutters.

Contact arms 23 and 24 are secured around the spindles at the center thereof between the split curved ends 22 of the shutters 20 and 21.

A pair of magnets 25 and 26 are mounted rearward of the reflector 14, and secured thereto, the forward portions of the magnets projecting through slotted apertures 27 in said reflector.

A lamp housing 28 is mounted below the middle 25 of the directional symbol housing 10 and secured thereto by bolts 29; and a lamp 30 is mounted in a socket 31 within the housing 28 and engages a contact spring 32 secured in said housing.

Ears 33 bent inwardly from the top edge of 30 the housing 10 provide means whereby a cover 34 may be mounted over said housing and secured by bolts 35 through the ears 33.

A switch 36 consisting of a pivotal top portion 37 and a stationary bottom portion 38 may be 35 mounted on the instrument board 39 as shown in Fig. 10 or on any suitable place.

The pivotal top portion 37 is secured to a hollow shaft mounting 40 by a bolt 41 projecting through a bore 42 in said top portion 37 and screwed into 40 the shouldered portion 40a which extends within an aperture 37a in the top portion.

A copper or brass contact plate 43 is mounted in a recess 44 in the top portion 37 adjacent to a contact post 45 secured therein; a stop 46 is 45 journaled in the top portion 37 near the bottom thereof and engages a loop 47 in a double spring 48 mounted in a slotted recess 49 in the stationary bottom portion 38 and projects downwardly within a smaller slotted recess 50.

A contact post 51 has a spring 52 mounted therebelow to keep the contact constant when the top and bottom portions 37 and 38 are assembled.

A pair of contact terminals 53 and 54 of stain- 55

less steel or the like, are respectively for controlling the left and right shutters 20 and 21 and are mounted on the stationary bottom portion on opposed sides thereof with a light breaker contact 55 at the top and between said contacts 53 and 54.

A conductor 56 leads from the breaker contact 55 to the lamp bulb 30 in the lamp housing 28, the return wire from the lamp being grounded, 10 the battery wire 57 being secured to the contact post 51 of the circuit. Conductors 58 and 59 are secured to the contact elements 53 and 54, respectively on the bottom portion 38.

Thus when assembled the pivoting top 37 may 15 be turned right or left to give a right or left turning signal, and the contact post 45 in the top portion 37 engages either the right shutter contact 54 or the left shutter contact 53 which closes the circuit through the magnet 25 or 26 which 20 causes the shutter 20 or 21 as the case may be, to close, and the contact points of the contact arms 23 or 24 thus contact the magnet 25 or 26 and the lamp 30 lights, illuminating the symbol 12a on the glass 12, the left shutter closing for a 25 left turn and the right shutter 21 for a right turn.

Thin clock springs 70 are secured to the reflector 14 by rivets 71 at one end, the opposite end is pivotally secured through an eye 72 in a 30 spring bracket 73 to the shutters 20 and 21, as illustrated in Fig. 2. Said springs 70 actuate the shutters as the contacts open and close.

The action of the shutter in closing causes the

covering of part of the symbol 12a, and the V cut in the shutter forms an arrow point by permitting the illumination of only that part of the symbol not covered by the shutter.

An angular license mounting 60 having slots 5 61 and 62 therein may be secured to the housing 10 by bolts 63.

This device may also be secured to the gear shift post 64 by a set screw 65 as shown in Fig. 7.

I claim:

1. A direction signal comprising a horizontally elongated housing having a face plate with a transparent direction arrow-shaped mark thereon, a concave reflector extending from end to end within the housing, a shutter pivotally mounted between each end of the reflector and the face plate and adapted to swing from and toward the latter to change the appearance of the corresponding end of the mark, an electromagnet disposed in each end of the housing behind the reflector and operatively controlling the shutter, and switch means to operate the magnets respectively, the axis of the shutter pivot extending vertically parallel to the plane of the reflector and the pivot being provided with a 20 contact arm extending behind the reflector to a 25 position in line with and opposite to the axis of the magnet.

2. A direction signal as in claim 1, the end of the reflector being slotted and the contact arm 30 extending through said slot.

FRANK VASARHELY.
